(57) **CLAIM**

The ornamental design for a flashing light shoe charm, as shown and described.

DESCRIPTION

FIG. 1 is a perspective view of a flashing light shoe charm showing my new design;

FIG. 2 is a front elevational view thereof;

FIG. 3 is a top plan thereof;

FIG. 4 is a bottom plan view thereof; and,

FIG. 5 is a perspective view of a flashing light shoe charm in a used condition.

The broken line showing of a shoe in FIG. 5 is included for the purpose of illustrating only and forms no part of the claimed design.
